UNITED STATES PATENT OFFICE.

GARABED G. HEGHINIAN, OF NEW YORK, N. Y., ASSIGNOR TO FLORENCE G. HAYDEN,
OF QUINCY, MASSACHUSETTS.

REINFORCEMENT FOR COMPOSITION COVERINGS FOR STRUCTURAL MEMBERS.

1,251,020.

Specification of Letters Patent. Patented Dec. 25, 1917.

Application filed December 14, 1914. Serial No. 877,100.

To all whom it may concern:

Be it known that I, GARABED G. HEGHINIAN, a citizen of the United States, and a resident of the city of New York, county 5 and State of New York, have invented certain new and useful Improvements in Reinforcements for Composition Coverings for Structural Members, of which the following is a full, clear, and exact description.

The invention relates to reinforcements for concrete and like fire-proofing composition coverings of structural members, and seeks to provide an improved reinforcement 15 which can be readily applied to structural members with the reinforcing elements thereof properly spaced from one another and from the member. More particularly, the invention seeks to provide a reinforcement of strong, braced construction, which can be securely connected to the structural member so that it cannot be displaced as the concrete or other composition is tamped into the molds. The invention consists in 20 25 the features of improvement hereinafter set forth, illustrated in the preferred forms in the accompanying drawings and more particularly pointed out in the appended claims.

In the drawings Figure 1 is a perspective view of the preferred form with the present improvement shown applied to the lower flange or soffit of an I-beam, and with a portion of the body of concrete in which the 30 35 I-beam is embedded indicated in dotted lines. Fig. 2 is a cross section of the lower portion of the I-beam with the improved reinforcement applied thereto. Fig. 3 is an inverted plan view of the parts shown in 40 Figs. 1 and 2. Fig. 4 is a cross section illustrating a slightly modified form of the improvement adapted for application to a channel bar.

The improved reinforcement comprises 45 two or more series of stays or reinforcing elements which are connected together to maintain the same in different, substantially parallel planes, and to brace or strengthen the separate elements. The reinforcement 50 is preferably expansible and the cross stays of each series are connected together and are adapted to extend back and forth over the face of the member to which the reinforcement is applied. In the preferred form 55 shown, the cross stays are connected against separation at the joints between the same so that the portions of the cross stays between the joints, when the reinforcement is expanded, extend back and forth in angular or zigzag fashion over the face of the 60 member.

As shown, two series of cross stays are preferably employed and the cross stays 10 and 10' of the two series are preferably formed of separate wires, each stay wire 65 being connected to the two adjacent stay wires of its series by short wire sections 11 welded thereto. While this manner of connecting or forming the joints between the stay wires forms stout joints and can be 70 inexpensively effected by electrically welding the short connecting pieces 11 to the stay wires, it is obvious that the stay wires may be otherwise connected in a manner permitting the separation of the cross stays 75 as the reinforcement is expanded.

The reinforcement is provided with offset extensions arranged to abut against the edges or flanges of the structural member and connections are also provided between 80 the two series of cross stays to maintain the cross stays of the separate series in different plane with each cross stay of one series substantially parallel to the adjacent cross stay of the other series. These extensions and 85 connecting elements preferably project from the expansion joints or connections between the cross stays and are preferably integral with the latter. For this purpose, each of the cross stays 10 of the upper or inner series is provided at one end with an integral extended portion 12 and each of the cross stays 10' of the lower or outer series is provided at one end with an integral extended portion 13, and these integral portions 90 extend from or beyond the joints or connections between the cross stays. The extensions 12 in the form shown in Figs. 1, 2 and 3 are bent upwardly and then inwardly to form attaching hooks 14, which are arranged to overlap the flanges 15 of the I-beam 16 to secure the reinforcement in place. The shanks 14' of the hooks are also arranged to abut against the edges of the flanges 15, as most clearly shown in Fig. 2. 105 Preferably also the portions of the extensions 12 between the attaching hooks and the expansion joints are bent inwardly to form portions 17 which are arranged to abut against the outer or lower face of the struc- 110

tural member and which are offset from the plane of the cross stays 10 so that the latter are spaced from the face of the member. It should be noted that the hooks 14 and the 5 offset portions or elements 17 form in effect jaw members which are offset from the plane of the cross stays 10 and which are spaced apart to receive the flanges of the structural member between them.

- 10 The extensions 13 preferably project laterally in the plane of the cross stays 10' and are then bent upwardly and inwardly and are rigidly connected to the hooks 14 preferably by means of short connecting pieces 15 18 welded thereto.

Before the reinforcement is applied in position the cross stays of each series are substantially parallel as indicated in the lower portion of Fig. 3, and, in this unexpanded 20 condition, the space between the hooks 14 at opposite sides of the reinforcement is such that they may be readily engaged with the flange of the structural member. When the reinforcement is expanded longitudinally of 25 the structural member, the cross stays spread apart in the zigzag arrangement shown in Fig. 1 and in the upper portion of Fig. 3, and the attaching elements or hooks are drawn inwardly into engagement with the 30 beam flange. It should be noted that the construction is such that the expansion of the reinforcement does not tend to distort the offset extensions 12 so that the engagement of the shanks 14' of the attaching 35 hooks with the edges of the flanges of the structural member, limits or arrests the expansion and thereby automatically determines the spacing of the cross stays. Moreover, the engagement of the spacing portions 40 or elements 17 with the outer or under face of the member prevents the cross stay 10' from being drawn in against the face of the member and thereby aids in limiting the expansion. It should also be noted that the 45 rigid connections between two series of stays serve to maintain the same in proper spaced relation with each cross stay of one series substantially parallel to the adjacent cross stay of the other series and the two series of 50 connected stays brace and strengthen one another so that they cannot readily be tipped, distorted or displaced when once put in position upon the beam. Furthermore, the extensions 12 and 13 brace one another and 55 form stout attaching elements which cannot be readily disengaged from the beam flanges as the concrete or other composition is tamped into the mold. It should also be noted that the extensions 13 project outwardly to a considerable extent beyond the 60 beam flanges and thereby serve to reinforce the portions of the body of concrete outside of the beam flanges. Inasmuch as these extensions are rigidly secured to the hooks or 65 attaching elements which snugly engage the

beam flanges these reinforcing extensions are securely held in proper position. It is important to brace and strengthen the parts of the reinforcements as above described since 70 expandible reinforcements of this sort are formed of soft annealed wire, and, unless the parts are properly braced and strengthened, they are apt to be distorted or moved out of proper position.

In the form shown in Fig. 4 the extensions 75 on one side of the reinforcement are similar to those previously described. On the other side, extensions 12' and 13' are provided with vertically disposed connected ends 19 which are adapted to abut against the outer 80 face of the web of the channel bar 20 and a portion of the extension 13' beyond the part 19 is upwardly offset to form a V-shaped seat 21 which is adapted to receive the lower hooked end 22 of a connecting 85 wire 23. This wire extends upwardly from the upper edge of the channel bar and is bent over the upper flange, as clearly shown in Fig. 4. One of these connecting wires is secured to each extension 13' of the reinforcement and serves to secure the latter in place and also to strengthen or reinforce the body or concrete covering on the outer 90 face of the web of the channel bar.

It is obvious that the extensions may be 95 otherwise bent to engage other forms of structural metal shapes, and that changes may be made in the details set forth without departure from the essentials of the invention as defined in the claims.

I claim as my invention:

1. A reinforcement for the composition covering of structural members comprising two expandible series of cross stays adapted to extend back and forth over the face of the member and connected together to maintain the cross-stays of the two series in different planes, and offset extensions from the cross stays for engaging the edges of the structural members.

2. A reinforcement for the composition covering of structural members comprising two series of cross stays adapted to extend back and forth over the face of the member, connections between the cross stays of each series for holding the same in proper spaced relation, connections between the two series for maintaining each cross stay of one series substantially parallel to the adjacent stay of the other series, and offset extensions from said cross stays for engaging the edges of the structural members.

3. A reinforcement for the composition covering of structural members comprising two series of connected cross-stays capable 125 of expansion longitudinally of the member and of contraction laterally thereof, connections between the two series of cross stays for maintaining the same in different planes with each cross stay of one series substan- 130

tially parallel to the adjacent stay of the other series, and offset attaching elements arranged to engage the structural member upon the expansion of the reinforcement to 5 secure the latter thereto.

4. A reinforcement for the composition covering of structural members comprising two series of cross stays, the cross stays of each series being connected at intervals 10 against separation and adapted to extend back and forth over the face of the member, connecting elements between the two series for maintaining the cross stays thereof in different planes, and offset attaching elements extending from some of the joints between the cross stays for engaging the edges of the structural member.

5. A reinforcement for the composition covering of structural members comprising 20 two expansible series of cross stays, the cross stays of each series being connected at intervals against separation and adapted to extend back and forth over the face of the member when expanded, connecting elements 25 between the two series for maintaining the cross stays thereof in different planes, each of said connecting elements being integral with a cross stay in one series and connected to a cross stay in the other 30 series, and certain of said cross stays having integral portions extending beyond the joints between the same and bent to form attaching elements.

6. A reinforcement for the composition 35 covering of structural members comprising two series of cross-stays, the cross-stays of each series being connected at intervals against separation to define an angular arrangement of the cross-stays, connections between the two series for maintaining the cross stays thereof in different planes with 40 each cross-stay of one series substantially parallel to the adjacent cross-stay of the other series, and offset extensions from said 45 cross-stays constituting attaching elements.

7. A reinforcement for the composition 50 covering of structural members comprising two expansible series of cross-stays, the cross-stays of each series being connected at intervals against separation to define an angular arrangement of the cross-stays when 55 expanded, offset extensions from certain of said cross-stays constituting attaching elements for engaging the edges of the structural members, and extensions from other cross-stays constituting connecting elements between the two series for maintaining the cross-stays thereof in different planes, said connecting elements projecting laterally beyond 60 said attaching elements.

8. A reinforcement for the composition 65 covering of structural members comprising two expansible series of cross-stays, the cross-stays of each series being connected at intervals against separation to define an an-

gular arrangement of the cross-stays when expanded, offset extensions from one series of cross-stays constituting attaching elements for engaging the edges of the structural member, and offset extensions from the 70 other series of cross stays connected to said attaching elements and constituting spacing and connecting elements between the two series for maintaining the cross-stays thereof spaced apart in different planes, said 75 connecting elements projecting outwardly beyond said attaching elements.

9. A reinforcement for the composition covering of structural members comprising two series of cross-stays, the cross-stays of 80 each series being connected at intervals against separation to define an angular arrangement of the cross-stays, integral offset extensions projecting from the joints between the stays of the inner series and bent 85 to form attaching hooks for engaging the flanges of the member, and integral offset extensions from the joints between the stays of the outer series connected to said attaching hooks and projecting outwardly beyond 90 the same to reinforce the composition body outside of the flanges of the member.

10. A reinforcement for the composition covering of structural members comprising two series of cross-stays, each cross-stay being connected or joined to the adjacent cross-stay of its series to define an angular or zig-zag arrangement of the cross-stays over the 95 face of the member, connections between the two series of cross-stays for maintaining 100 the same in different planes with one series further from the face of the member than the other, and offset attachment elements extending from said cross-stays for engaging the edges of the structural member. 105

11. A reinforcement for the composition covering of structural members comprising two series of cross stays adapted to extend over the face of the member, connections between adjacent stays and between the two series of stays arranged to maintain the adjacent stays in proper spaced relation and the two series of stays in different planes with one series farther from the face of the member than the other and offset attaching elements extending from said cross stays for 110 engaging the edges of the structural member. 115

12. A reinforcement for the composition covering of structural members comprising two series of stays, connections between the 120 individual stays arranged to hold the same against tipping and in proper spaced relation, connections between the two series of stays arranged to maintain the same in different planes with one series farther from 125 the face of the member than the other, and offset attaching elements extending from said stays for engaging the edges of the structural members.

13. A reinforcement for the composition 130

covering of structural members comprising two series of cross stays adapted to extend over the face of the member, the cross stays of each series being connected at intervals 5 against separation to hold the same in proper spaced relation and offset extensions from certain of said cross stays constituting attaching elements arranged to engage the edges of the structural members and offset 10 extensions from certain of said cross stays connected to and bracing said attaching elements and constituting spacing and connecting elements between the two series of cross stays for maintaining the same spaced apart 15 in different planes.

14. A reinforcement for the composition covering of structural members comprising two expandable series of cross stays, the ad-

jacent cross stays of each series being joined at intervals against separation to define an angular arrangement of the cross stays when expanded, integral offset extensions projecting from the joints between the stays of one series and shaped to form attaching elements for engaging the edges of the structural member, and integral offset extensions projecting from the joints between the stays of the other series connected to and bracing said attaching elements and constituting spacing and connecting elements for holding the two series of stays in different planes.
